Application July 22, 1949, Serial No. 4,064

Term of patent 3½ years

(Cl. D14—3)

To all whom it may concern:

Be it known that we, Robert M. Huffaker, Daniel S. Larson, Edmund J. Laue, Richard E. Reedy, and Russell G. Davis, citizens of the United States, residing at the city of Columbus, county of Franklin, and State of Ohio, have invented a new, original, and ornamental Design for Trailer, of which the following is the specification, reference being had to the accompanying drawings, forming a part hereof.

Fig. 1 is a forward elevational perspective view of our trailer taken on the left hand side;

Fig. 2 is a rearward elevational perspective view of the same taken on the left hand side; and

Fig. 3 is a side elevational view taken on the right hand side of the trailer.

The characteristic features of our design reside in the portions shown by means of full lines in the drawing.

We claim:

The ornamental design for a trailer, as shown and described.

ROBERT M. HUFFAKER.
DANIEL S. LARSON.
EDMUND J. LAUE.
RICHARD E. REEDY.
RUSSELL G. DAVIS.
